United States Patent Office

Des. 223,624
Patented May 16, 1972

223,624

COMBINED DIAL AND HANDS FOR A WATCH OR THE LIKE

Sondra J. Sicherman, Fresh Meadows, N.Y., assignor to Startime Watch Co., Inc., Roslyn, N.Y.

Filed Nov. 4, 1970, Ser. No. 25,815

Term of patent 3½ years

Int. Cl. D10—07

U.S. Cl. D42—1

Fig. 1

Fig. 2

FIG. 1 is a top view of a dial for horological devices showing my design; and

FIG. 2 is an edge view thereof.

I claim:

The ornamental design for a combined dial and hands for a watch or the like, substantially as shown.
